TUMBLING APPARATUS FOR DEGREASERS

Willard D. Phillips and Ralph A. Van Fossen,
Chicago, Ill.Original application August 3, 1940, Serial No.
351,018. Divided and this application Febru-
ary 15, 1943, Serial No. 475,915

2 Claims. (Cl. 202—170)

This invention is a division of my co-pending application Serial No. 351,018, filed August 3, 1940, and relates to a degreasing apparatus and particularly to a new and improved degreasing cabinet having certain inherent advantages not contemplated in the prior art. One of the objects of the invention is to provide a degreasing cabinet with a new and novel mechanical design wherein a cabinet of comparatively small size and weight is arranged to include a relatively large vapor treating chamber adapted to handle large and heavy machinery.

The particular object of the invention is to provide a work container arranged to facilitate lowering small metal parts into the vapor chamber and adapted to automatically tumble these parts coincidental to the removal of the container from the vapor to prevent trapping liquid solvent in any cups or cup shaped portions which might be included in the parts being treated.

Referring now more particularly to the drawing:

The single figure is a side elevation sectional view of our degreaser showing one form of a removable support with a tumbling cylinder arranged to be inserted into and withdrawn from the vapor treatment chamber as will later be explained.

The method of operation of a vapor type degreasing apparatus is well understood in the art and consists of lowering relatively cool metal parts into the vapor chamber to allow the heated hydro-carbon vapors to condense on the surfaces of the metal and flush oils, greases, or other impurities from these metal surfaces into the vaporizing sump of the degreasing apparatus. Some difficulty has arisen in the prior art when attempting to treat small stampings or drawn metal parts or other pieces having cup shaped portions or depressions by reason of the fact that the liquid condensate would become trapped in the cup shaped portions and could not be removed from these surfaces until the parts had been removed from the vapor chamber and inverted into some other container.

This difficulty is overcome in the present invention by providing a tumbling cylinder arranged so that small metal parts may be introduced into the vapor chamber and will undergo a tumbling action coincident with the removal of the parts from the chamber so that any liquid solvent will be immediately discharged and will not be carried beyond the upper limit of the vapor cabinet. To accomplish this an inclined

framework 101 is provided in the vapor chamber 76, and while this framework 101 is subject to numerous modifications of structure, it is preferable to provide a pair of angle iron rails 102 being curved at their lower ends to form a seat 103 and similarly curved at their upper ends to form a seat 104. The rails 102 are rigidly connected by suitable angle irons 105, 106, 107 and 108 to maintain proper spacing and to give rigidity to the structure including its support on the degreaser, thus facilitating the movement of the tumbling cylinder along the rail surface.

The tumbling cylinder comprises a perforated drum 111 provided with end plates 112 including hub portions 113 in which a handle 114 is mounted. The handle 114 is sufficiently long to extend above the upper surface of the vapor cabinet when the tumbling cylinder is at its lowermost position so that the cylinder may be withdrawn by manual manipulation of the handle. As the cylinder is withdrawn the outer surface of the drum 111 will ride upwardly along the flanges 115 of the angle iron 102 and as the cylinder reaches the upper seat 104, each of the hub portions 113 will come to rest in the notches 116 formed in supporting bars 117 secured to the angle iron rolls 102 by a plurality of rivets 118. From an examination of the drawing illustrated in the figure it will be seen that the comparative dimensions of the tumbling cylinder of the inclined rails are such that as the cylinder rolls upwardly along the rails it will be inverted twice so that any liquid solvent which may be trapped in cup shaped portions of metal parts will be discharged before the cylinder comes into position at the seat 104.

The operator may open the loading door 121 and then manually invert the cylinder to discharge the parts contained therein into any convenient receptacle, as for example the tray 122. The cylinder 111 is then again loaded and rolled down the inclined rails 115 to begin the next subsequent operation. It is to be understood, of course, that the tumbling cylinder and rails illustrated in the figure is removable from the vapor chamber when it is desired to treat large castings, etc., and it should be further pointed out that this tumbling cylinder with its removable rail supports may be applied to any suitable degreaser. It will be understood that many modifications in structure are possible and we do not desire to be limited to the structure shown except as such limitations are imposed by the claims.

Having thus shown and described our invention, we claim:

1. In a portable degreasing apparatus, comprising a chest having a condenser mounted adjacent its inner rim, a vapor generator in the bottom, and a vapor treating chamber between the generator and condenser; the combination with a tumbling apparatus comprising a frame consisting of a pair of spaced apart rails interconnected by cross beams and adapted to be positioned at an incline within the vapor chamber with the lower end below the vapor level; a tumbling basket consisting of a foraminated cylinder, a handle mounted on said cylindrical basket, the arrangement being such that the cylindrical basket may roll down the inclined rails to enter the degreasing vapor chamber and roll upwardly along said rails as the cylindrical basket is removed from the vapor chamber to effect repeated tumbling of the contents of said basket.
2. In a portable degreasing apparatus, com-

prising a chest having a condenser mounted adjacent its inner rim, a vapor generator in the bottom, and a vapor treating chamber between the generator and condenser; the combination with a tumbling apparatus comprising a frame consisting of a pair of spaced apart rails interconnected by cross beams and adapted to be positioned at an incline within the vapor chamber with the lower end below the vapor level and the upper end extending out of the vapor chamber; a tumbling basket consisting of a foraminated cylinder including a door in the cylindrical surface and having a handle pivotally mounted on the axis of said cylindrical basket, the arrangement being such that the cylindrical basket may roll down the inclined rails to enter the degreasing vapor chamber and roll upwardly along said rails as the cylindrical basket is removed from the vapor chamber to effect repeated tumbling of the contents of said basket.
